UNITED STATES PATENT OFFICE.

FRANK H. MARK AND HOMER J. MCCONOCHY, OF PORTLAND, INDIANA, ASSIGNEES,
BY MESNE ASSIGNMENTS, TO THE HOT PRONG CARBURIZER COMPANY, OF PORT-
LAND, INDIANA, A CORPORATION OF INDIANA.

ELECTRIC FUEL VAPORIZER.

Application filed January 6, 1922. Serial No. 527,502.

To all whom it may concern:

Be it known that we, FRANK H. MARK and HOMER J. MCCONOCHY, both citizens of the United States, residing in the city of Portland, in the county of Jay, State of Indiana, have jointly invented a new and useful Electric Fuel Vaporizer, of which the following is a full, clear, and comprehensive specification and exposition, the same being such as will enable others to make and use the same with exactitude.

The object of our present invention, broadly speaking, is to provide an electric fuel-vaporizer for internal combustion motors, the same being of simple construction, adapted to be easily and quickly installed in connection with the fuel system, the same being inexpensive in maintenance, easily operated and controlled, and which can be manufactured and sold at a comparatively low price.

The specific object of this invention is to provide an economical and highly efficient means for quickly vaporizing liquid fuel as the fuel passes from the carburetor into the manifold, the same being especially applicable when the motor, and the other parts, are cold thereby enabling one to start a very cold motor as easily as it would be if the motor was hot.

Other minor objects and particular advantages of the invention will suggest themselves in the course of the following description and that which is new will be correlated in the appended claims.

The preferred means for carrying out the objects of our invention in a practical and mechanically efficient manner is shown in the accompanying drawings, in which—

Figure 1 shows in elevation the upper portion of a carburetor and the lower portion of an intake manifold, showing our invention as installed in operative condition therebetween, and also showing the electrical connections of the invention.

Figure 2 shows a plan view of the body portion of the device, showing certain portions as broken away to more clearly show the construction.

And Figure 3 is a central cross section of the main portion or body of the invention, as taken on the line 3—3 of Fig. 2.

Similar indices denote like parts throughout the several views.

In order that the construction, the operation, and the advantages of the invention may be more fully understood and appreciated, we will now take up a detail description thereof, in which we will set forth the invention as fully and as clearly as we may.

Referring now to the drawings in detail: Letter A denotes the upper end or flange of a carburetor. B denotes the lower flange of the intake manifold D, the flanges A and B being identical with each other, and they are ordinarily contacted with each other, or with a gasket therebetween, and they are adapted to be tightly clamped and secured together by the screws or bolts C—C.

Our invention comprises a body 1 whose outline shape corresponds with the shape of the flanges A and B, and having bolt notches 2 and 3 formed in its end portions to register with the bolt apertures in the flanges A and B.

A central aperture 4 is formed through the body 1 and it corresponds in size with the passageways in the upper portion of the carburetor and the lower portion of the manifold. Located in the center of the aperture 4 is a disc 5, in the center of which is an aperture 6. The disc 5 is integrally connected with the body 1 by the arms 7 and 8. Said disc 5 and the arms 7 and 8 are of less thickness than the body 1, and they are located in line with the lower face thereof, substantially as shown in Fig. 3.

Also extending into the aperture 4, from the body 1, are the two oppositely disposed wings 9 and 10. Said wings are of the same thickness as are the disc 5 and the arms 7 and 8, and they are located on a level therewith, as in Fig. 3. A plurality of small apertures E are formed through the disc 5, the arms 7—8, and the wings 9 and 10, through which vapor may pass as it is being gasified.

Numerical 11 denotes a wire screen which is fitted in the aperture 4 above the disc 5, the arms 7 and 8, and the wings 9 and 10 which serves to catch globules of gasoline which might pass upward thereto and by which it would be retained until gasified.

Formed around in a circle in the body 1 and concentric of the aperture 4 and a short distance therefrom, is a channel 12 in which is located the endless resistance coil 13.

Said coil is packed in a special cement by which the coil is insulated from the metal of the body 1, and when said cement solidifies it forms not only an insulator but 5 acts as a radiator element for the heat which is generated in the coil.

At one point the coil 13 is grounded to the body 1 by means of a screw 14, or other means. Directly opposite to the screw 14 a 10 wire 15 is connected to the coil 13 and it extends outward therefrom through an aperture formed therefor in the body 1.

Numerals 16 and 17 denote gaskets, each corresponding in outline with the peripheral shape of the body 1, and with the central portion of said gaskets cut-away to form apertures therethrough of a size equal to the size of the central aperture 4.

The body portion of the device is placed 20 in position as follows: The bolts C—C are first removed, allowing the flanges A and B to be spaced apart, after which the body 1, together with the gaskets 16 and 17 on each side thereof, are then placed between the 25 flanges A and B, after which the bolts C—C are again inserted, this time passing through the apertures 2 and 3 and the similar apertures of the gaskets, and as said bolts are tightened the body 1 will be 30 clamped in operative position as is shown in Fig. 1.

Numeral 18 denotes an electric switch, of ordinary construction, having a push button 19 in connection therewith. Said switch 35 should be secured to the instrument board and within reach of the driver of the automobile with which it is connected. The wire 15 is extended to and is secured to one pole of the switch, as shown. A wire 20 is extended 40 from the other pole of the switch to one pole of the ammeter X located on the instrument board, thereby completing the electrical connection with the storage battery and with our vaporizer or sub-car- 45 buretor.

It is now evident that if the switch be closed that an electric current will flow from the battery, through the wires 20 and 15, to the coil 13, the return current being through 50 the ground 14, thereby causing the coil to heat and by which the adjacent parts, particularly the inner wall of the body 1, the arms 7 and 8, the disc 5, and the wings 9 and 10, will be heated whereby the gas or gaso- 55 line which passes through the central aperture of the body 1 will be heated whereby it becomes volatile and highly explosive before it enters the manifold D.

Therefore it is apparent that by the employment of our invention the fuel passing 60 into the firing chambers of the motor will be easily exploded, thereby making the starting of the motor as easy in cold weather as when the atmosphere is warm.

55 In practice the first thing to do when one

desires to start his cold motor is to close the switch 18 to establish the electric circuit, and allow a short time, one or two minutes, for the coil to heat up the adjacent parts. The motor may then be started in the usual manner but permitting the switch to remain closed until the motor is thoroughly warmed, after which the switch may be opened to cut off the current from the coil.

It is to be understood that our body member 1 is not limited to the position as shown, as in some cases it may be best to employ it the other side up from that shown, that is with the screen 11 below the disc 5. In fact the screen 11 may be entirely dispensed with 80 in some instances.

We also desire that it be understood that various other changes may be made in the several details of construction shown without departing from the spirit of the invention and without sacrificing any of the advantages thereof which are new and useful.

Having now fully shown and described our invention, what we claim and desire to secure by Letters Patent of the United States, is—

1. A fuel-vaporizer comprising a flat body having a central aperture therethrough, an electric heater located in a channel formed in one face of the body and concentric of the central aperture, means for conducting electric current to said coil, means for grounding the coil, baffles of less thickness than said body extending from the body into said central aperture, and a screen carried by the body and extending across said central aperture therethrough, all substantially as shown and described. *

2. An electric fuel-vaporizer comprising a flat body having a central aperture therethrough and adapted to be clamped between the flange of a manifold and the flange of a carburetor, gaskets spacing said body from said flanges, an electric heat producing means extending entirely around said aperture in the body and located entirely in a channel formed in one face of the body, an electric conductor extending through the edge of the body to the heat producing means, and a grounding means connected to 115 said heat producing means, all substantially as shown and described.

3. An electric fuel vaporizer comprising, in combination, a body member adapted to be secured between a carburetor and a manifold of an explosive motor, an endless resistance coil imbedded in said body concentric of the passage-way therethrough, means for insulating said coil from the body, means for conducting electric current 125 through said coil, and baffles extending from said body into the central aperture therethrough, all substantially as shown and described.

4. An electric fuel vaporizer comprising 130

a flat body adapted to be clamped between the carburetor and the intake manifold of an explosive motor and having a central aperture therethrough registering with the fuel apertures of the carburetor and the manifold, an endless electrical coil located in a channel formed in said body and concentric of said central aperture, means for insulating said coil from the body, means 10 for conducting electric current through said coil, a disc located in the center of said aper-

ture, arms connecting said disc with the body, and wings extending from the body into said aperture, there being apertures formed through said disc, the arms, and 15 wings, and the disc, the wings, and the arms being of less thickness than the body, all substantially as shown and described.

In testimony whereof we have hereunto subscribed our names.

FRANK H. MARK.

HOMER J. McCONOCHY.
